UNITED STATES PATENT OFFICE.

JOSEPH WILLIAM GUIMONT, OF LACHINE, QUEBEC, CANADA, ASSIGNOR OF ONE-HALF
TO LUDGER LEMIEUX, OF MONTREAL, CANADA.

RADIATOR SECTION.

Application filed August 5, 1926. Serial No. 127,201.

The present invention pertains to a novel radiator section of the type which forms a separable unit in a complete radiator.

The principal object of the invention is to provide a passage running longitudinally through the section and open to the atmosphere, whereby the area of contact between the atmosphere and the heated walls of the section is increased. Hitherto this result has been obtained by passing pipes or tubes through the section and fastening them in the top and bottom of the section. This construction is, however, defective in that it increases considerably the cost of installation and results in a radiator of awkward appearance.

The present invention overcomes these defects by providing a radiator section cast in such a way that, when assembled, the air passages will be formed without the insertion of separate tubes. Each radiator section is cast in two parts called semi-sections, each of which has a straight inner wall with a depression running longitudinally thereof. When two semi-sections are assembled, the depressions in the inner walls are brought together so that a continuous opening is formed from top to bottom without changing the exterior appearance of the radiator, except that the ends of the passages are visible. The semi-sections are joined preferably by means of hollow nuts threaded through the straight walls and inserted through the usual circulation ports.

The invention is fully disclosed in the following description and in the accompanying drawings in which;

Figure 1 is an outside elevation of a radiator section constructed according to the invention;

Figure 2 is an elevation at the inner wall of one of the semi-sections;

Figure 3 is a section on the line 3-3 of Figure 1;

Figure 4 is a section on the line 4-4 of Figure 1; and

Figure 5 is a section on the line 5-5 of Figure 1.

Reference to these views will be made by use of like characters which are employed to designate corresponding parts throughout.

The radiator section constructed according to the invention is of the two branch type comprising branches 1 and 2 with an air

space 3 therebetween. The section is constructed of two semi-sections of substantially the same configuration. The semi-sections are formed by passing a plane through the branches 1 and 2 in such a manner as to bisect them.

Each semi-section comprises therefore an outer curved wall 4 for each branch as shown more clearly in Figure 5. The edges of the wall 4 are joined by a straight inner wall 5 whereby an enclosure 6 is formed. A depression 7 is made in each inner wall so that when the semi-sections are assembled, the depressions in adjacent walls 5 form an air space 8 extending longitudinally of the branches 1 and 2 and open at the top and bottom.

The branches 1 and 2 are joined at the top and bottom as indicated by the numerals 9 and 10 respectively in Figure 1, and the walls 5 of each semi-section are therefore also united as designated by the numeral 11 in Figure 3. The semi-sections are joined at these regions, namely at the top and bottom, where the walls 5 are connected. The connecting means consists preferably of hollow nuts 12 threaded through the contacting inner walls 5 and disposed preferably in line with the usual circulation ports 13 through which they are introduced within the section. It will be readily apparent, especially from Figure 3, that the hollow character of the nuts 12 provides communication between the enclosures 6 of the two semi-sections.

One of the curved walls 4 of each semi-section is formed with continued flanges 14 in which the adjacent curved wall of the other semi-section is received. The flanges of one branch are preferably directed oppositely to those of the other branch as shown in Figure 5.

While a specific embodiment of the invention has been illustrated and described, it is to be understood that various alterations in the details of construction may be made without departing from the spirit of the invention as indicated by the appended claims.

Having thus fully described the invention, what I claim as new and desire to protect by Letters Patent is:

1. A radiator section comprising two semi-sections of like formation, each semi-section having an inner wall and a curved outer wall forming an enclosure having the

height and substantially half the width of a complete section, the inner wall of each semi-section having a depression therein, the inner walls and depressions of the semi-sections being coincident in the assembled section, and hollow nuts passed through said inner walls at the top and bottom thereof for securing said semi-sections together.

2. A radiator section comprising two semi-sections of like formation, each semi-section having an inner wall and a curved outer wall forming an enclosure having the height

and substantially half the width of a complete section, the inner wall of each semi-section having a depression therein, the inner walls and depressions of the semi-sections being coincident in the assembled section, circulation ports formed in said outer walls, and hollow nuts passed through said inner walls in alinement with said ports, for securing said semi-sections together. 15
20

In witness whereof I have hereunto set my hand.

JOSEPH WILLIAM GUIMONT.
